LAMP BASING MACHINE

Harold E. Baker, Danvers, and Joseph H. Brooks,
West Peabody, Mass., assignors to Sylvania
Electric Products Inc., Salem, Mass., a corpo-
ration of Massachusetts

Application June 16, 1951, Serial No. 231,964

2 Claims. (Cl. 263—8)

1

This invention relates to apparatus for basing electrical devices and more particularly to a fluorescent lamp basing machine.

An object of this invention is to facilitate the application of bases to electrical devices.

Another object is to provide an apparatus for automatically basing electrical devices.

A further object is to provide an apparatus for automatically basing an electrical device, such as a fluorescent lamp, at both ends at the same time.

In the art of basing electrical devices, such as radio tubes and incandescent lamps, it has been the practice to position these devices on an apparatus, commonly known as a "basing reel," where the basing operation is performed. Normally the devices are disposed with their longitudinal axes disposed in a vertical plane. In the manufacture of fluorescent lamps, which are provided with a base at each end thereof, an apparatus such as that shown in U. S. Patent 2,264,304 issued December 2, 1941, to Gardner and entitled "Lamp Basing Machine" has been employed. In apparatus of this type, the ends of the lamp are based separately, i. e., after one end has been based, the lamp is rotated 180° and the other end is then based.

Desiderata of importance in fluorescent lamp manufacture have been the basing of both ends of the lamp simultaneously and the effecting of this operation with the longitudinal axis of the lamp disposed in a horizontal plane. Both of these goals have been attained in accordance with the principles of the instant invention, one embodiment of which is illustrated in the accompanying drawings in which:

Figure 1 is an elevational view of a fluorescent lamp basing machine.

Figure 2 is an end elevational view on an enlarged scale of a pair of basing heads on a conveyor showing the means for actuating them.

Figure 3 is a plan view partly in section of a basing machine head unit looking in the direction 3—3 of Figure 1, with the movable jaw on the left side omitted for clarity of illustration.

Figure 4 is an enlarged fragmentary detail view looking in the direction 4—4 of Figure 1 showing the means for actuating the basing heads.

Figure 5 is a fragmentary detail view of an end of a based fluorescent lamp.

Referring now particularly to Figures 1 and 3, wherein there is shown a specific embodiment of a basing machine comprising a pair of spaced endless chains 10 on which a plurality of head-carrying bars 12 are mounted, chains 10 are mounted on sprocket wheels 14, 16 and 18, and are driven by motor 20 through drive shaft 22 on which sprocket wheel 14 is mounted. The chains ride on chain tracks 24 mounted on transverse angle bars 26 of the basing machine frame 60.

2

28. Each head-carrying bar 12 has a basing head 30 mounted on each end thereof. Lamps 32, with bases 34 loosely positioned at the ends thereof and lead-in wires 38 threaded through base pins 32, are fed to heads 30 from lamp-feeding conveyor 34. The lamps 32 are loosely seated in V-shaped heads 36 on the conveyor 34 and drop therefrom into basing heads 30. Chains 10 on which head-carrying bars 12 are mounted, then carry lamps 32 with bases 34 loosely positioned on the ends thereof to a plurality of stations on the basing machine frame 28 at which heat, supplied by gas burners 38, is applied to the lamp bases to cure the basing cement 36 disposed therein to thereby effect the basing operation. The bank of gas burners 38 are mounted in a manifold 40 attached to the machine frame 28 and which is supplied with gas from a suitable source (not shown). After the basing operation has been completed, the basing heads 30 release the lamps, thus permitting them to roll down a track 42 onto a lamp-receiving table 44.

Referring now to Figures 2 and 3, each basing head 30 comprises a fixed jaw 46 and a movable jaw 48. The fixed jaw 46 is mounted on a bracket 50 and the movable jaw 48 is attached to an end of a lever 52 which is pivotally mounted intermediate its ends on a shaft 54 in bracket 50. As best shown in Figure 3, the left hand bracket 50 is fixedly mounted on a plate 53 which is fixedly attached to the head-carrying bar 12 by bolts 55 whereas the right hand bracket 50 is fixedly mounted on slide 56 which is disposed on the head-carrying bar 12. The slide 56 is provided with a pair of depending bolts 58 which extend through an elongated slot 60 in the bar 12 and thereby guide the slide 56 during its stroke, the nature and purpose of which are hereinafter described.

40. Each of the shafts 54, on which the levers 5 are mounted, is supported in a bearing 62 and is provided with a spring 64 concentric therewith which loads the lever 52 to maintain the jaws 46 and 48 normally closed to one another. A pair of bar cams 66, mounted on tracks 24, at each 45 side of the machine frame 28, are engageable by cam rollers 68 on the free end of levers 52 during a portion of the basing machine operating cycle to open the jaws as shown in Figure 2.

Referring now to the right hand side of Figure 3 and Figure 4, the slide 56 has a stud 70 depending therefrom and extending through the slot 60 in the bar 12. A cam roller 72, attached to the free end of stud 70, engages a bar cam 74, mounted on a cam support 75 mounted on angle bars 26, during a portion of the basing machine operating cycle and thereby effects a traversing stroke of the slide 56 on the bar 12. The slide 56 is normally maintained in the in position by a spring 76 supported on a stud 78 upstanding

on the bar 12 and the bearing 62 upstanding on the slide 56 (Fig. 3). When the slide 56 is moved outwardly by the bar cam 74, a load is placed on the spring 76 and this load effects a return of the slide when the cam roller 72 moves out of engagement with the cam 74.

The operating cycle of the above-described apparatus will now be described. Referring now to Figure 1, as the chains 10, on which the head-carrying bars 12 are mounted, move around sprocket wheels 16 and upwardly along the chain tracks 24, the basing heads 30 are brought into engagement with certain head-actuating mechanisms described above viz., the bar cam 74 which displaces the right hand heads in Figure 4 to the right, and the bar cams 66 which open the movable jaws 48. Both of these operations are performed to permit the basing heads 30 to receive the lamps 32 and their bases 84 as they are fed thereto by the feeding conveyor 34.

Referring now to Figures 3 and 4, as the chains 10 move the head-carrying bars 12 upwardly, the cam roller 72 engages the bar cam 74 and the cam rollers 68 engage the bar cams 66. As the cam roller 72 rides along the bar cam 74 it effects a displacement to the right of the slide 56 through the stud 70. This effects a similar displacement of the right hand head 30 since it is mounted on the bracket 50 which is attached to the slide 56. At the same time that this lateral displacement of the slide 56 is taking place, the cam rollers 68 are riding along the bar cams 66 to effect an opening of the movable jaws 48. Displacement of the cam rollers 68 by the bar cams 66 causes the levers 52 to rotate about the axes 35 of the shafts 54 on which they are mounted (Figs. 2 and 3) thereby opening jaws 48.

After the right hand head 30 has been displaced to the right and both movable jaws 48 have been opened, a lamp 32 is dropped into the heads 30 from the heads 36 on the feeding conveyor 34 (Fig. 1).

As the lamp 30 is carried upwardly (Fig. 4), the contours of the bar cam 74 and bar cams 66 are such that, through their respective cam rollers, a return of the slide 56 to the left and a closing of movable jaws 48 are effected. Closing of the jaws 48 as the rollers 68 ride off of bar cams 66 is shown clearly in Figure 2, the lamp 32 being omitted in the right hand head 30 for clarity of illustration. The movable jaws 48 on each end of the head-carrying bar 12 are snapped to a positive closed position by the springs 64 on which a load was placed due to the rotational displacement of the levers 52. Return of the slide 56 to the left as the cam roller 72 moves off of the high point of the bar cam 74 and eventually out of contact therewith is effected by the spring 76 on which a load was placed during the stroke of the slide 56 to the right.

With the lamp 32 and the bases 84 held firmly between the heads 30 and the jaws 46 and 48 of each head closed, the lamp is carried upwardly to a series of heating stations (Fig. 1) where 65 heat from the burners 38 cures the basing cement 86 (Fig. 5) which is disposed within the bases 84.

After the basing cement has been cured the lamp 32 travels over sprocket wheel 18 (Fig. 1) 70 and down the left hand side of the machine frame 28 for eventual discharge to the lamp-receiving table 44. Before the lamp 32 can be discharged, the slide 56 on the head-carrying bar 12 must

be displaced and the movable jaws 48 opened in order to free the lamp. The mechanisms for effecting these two operations are the same as those described above for preparing the basing heads 30 for receiving a lamp prior to the basing operation. Displacement of the slide 56 is effected by a bar cam 74 and the movable jaws 48 are opened by bar cams 66. When slide 56 and the jaws 48 are actuated the based lamp 32 rolls down the track 42 to the lamp-receiving table 44.

What we claim is:

1. Apparatus for securing a base, having a thermo-setting cement disposed therein, to each end of an elongated tubular electric lamp simultaneously, said apparatus comprising: a conveyor; a bar mounted on said conveyor transversely thereof; a pair of separable heads mounted at the ends of said bar for receiving a base and supporting the lamp; means for reciprocably placing said heads longitudinally with respect to one another to admit therebetween a lamp with a base positioned on each end thereof and to effect end-on engagement of the bases with said heads; means for opening and closing each of said heads for sequentially receiving, securing and freeing a lamp base; and heating means disposed adjacent to the path traversed by said heads on said conveyor for curing the thermo-setting cement disposed in the bases and thereby effecting attachment of the bases to the ends of the lamp.

2. Apparatus for securing a base, having a thermo-setting cement disposed therein, to each end of an elongated tubular electric lamp simultaneously, said apparatus comprising: a conveyor; a bar mounted on said conveyor transversely thereof; a plate fixedly mounted on said bar at one end thereof; a slide mounted on said bar at the other end thereof; a pair of heads for receiving the bases and supporting the lamp, one of said heads being mounted on said plate and the other of said heads being mounted on said slide, and each of said heads comprising a pair of jaws; means for reciprocating said slide to displace the head mounted thereon longitudinally with respect to the head mounted on said plate to admit therebetween a lamp with a base positioned on each end thereof, and to return the head mounted on said slide to effect end-on engagement of the bases with said heads; means for opening and closing the jaws of each of said heads for sequentially receiving, securing and freeing a lamp base; and heating means disposed adjacent to the path traversed by said heads on said conveyor for curing the thermo-setting cement disposed in the bases and thereby effecting attachment of the bases to the ends of the lamp.

HAROLD E. BAKER.
JOSEPH H. BROOKS.
